Primary Examiner — Rashida C. Walshon*(74) Attorney, Agent, or Firm* — Pauley Erickson & Swanson**CLAIM**

The ornamental design for a snowboard boot upper, as shown and described.

DESCRIPTION

FIG. 1 is a left side view of a snowboard boot upper, showing the design;

FIG. 2 is a right side view thereof;

FIG. 3 is a front side view thereof;

FIG. 4 is a back side view thereof;

FIG. 5 is a top side view thereof;

FIG. 6 is a bottom side view thereof;

FIG. 7 is a right perspective view thereof; and,

FIG. 8 is a left perspective view thereof.

Portions of the snowboard boot upper shown in broken lines form no part of the claimed design.

1 Claim, 7 Drawing Sheets(56)
